2 Claims. (Cl. 174—153)

This invention relates to a resiliently supportable, rigidly held feed-through terminal which is mounted on a panel for subsequent electrical connections.

In the manufacture of electronic apparatus, it is frequently necessary to provide panel structure adjacent to the apparatus having terminals mounted therein to facilitate the connecting of such apparatus with other apparatus. However, a frequent problem is encountered wherein a terminal is provided with a resilient support for mounting within the panel and such resilient support is not capable of sustaining heat upon the terminal during subsequent soldering operations. In addition, when a highly resilient material is utilized to support the terminal for subsequent insertion into an aperture of a panel, such resilient material does not provide adequate rigidity in supporting the terminal.

It is, therefore, an object of this invention to provide a feed-through terminal resiliently supported for subsequent insertion into a panel wherein the supporting structure is capable of sustaining heat subjected to the terminal during subsequent soldering operations.

Another object of the invention is the provision of a feed-through terminal which is resilient for insertion into a panel and when mounted within the panel is rigidly supported to preclude undesirable movement.

With these and other objects in view, the present invention contemplates a feed-through terminal having a central conductive terminal element with a relatively rigid insulating material surrounding an intermediate portion of the terminal and a comparatively resilient insulating material surrounding the rigid material.

Other objects and advantages of the invention will appear from the following detailed description of a specific embodiment thereof when read in conjunction with the appended drawings in which:

FIG. 1 is a perspective view of a feed-through terminal showing a terminal element extending through supporting structure, and

FIG. 2 is a sectional view taken along line 2—2 of FIG. 1 showing the feed-through terminal mounted within a panel.

Referring to FIGS. 1 and 2, a feed-through terminal 11 is provided with a rodlike conductive terminal element 12 having flat portions 13 formed on opposite ends thereof. A cylindrical inner support 14 is composed of a thermosetting plastic material, for example a phenolic resin, and concentrically surrounds and supports an intermediate portion of the terminal element 12. The support 14 is further formed with a circular flanged section 15 having a buffer 20 tapering outwardly at one end thereof, an annular anchoring rib 16 about an intermediate portion of the periphery thereof and a reduced neck 17 at the opposite end thereof. It is noted that the thermosetting plastic material has heat resistance properties which are capable of sustaining heat subjected to the terminal element 12 when the flats 13 of the terminal are soldered with other elements to provide an electrical connection. In addition, the thermosetting plastic material utilized in the support 14 provides a strengthening property to rigidly support the terminal element 12 in an aligned orientation against undesirable

2

movement of the terminal element when subjected to outside forces. The outer surface of the terminal element 12 is formed with anchoring projections 23 adjacent the support 14 to preclude sliding movement of the element within the support 14. An outer gripping cup-like shell 18 composed of a thermoplastic material, for example an acetal copolymer, is formed about the main portion of the support 14 to provide a resilient covering for the support.

As shown in FIG. 2, the shell 18 is formed with an annular groove 19 about an intermediate portion of the inner wall thereof wherein the groove cooperates with the annular rib 16 of the support 14 to anchor the shell to the support. A panel 21 having an aperture 22 is shown in FIG. 2 in sectional form to reveal the manner in which the feed-through terminal 11 is mounted to the panel. The resilient nature of the shell 18 facilitates the manual insertion of the feed-through terminal 11 within the aperture 22 of the panel 21. The flange 15 of the support 14 precludes movement of the feed-through terminal in one direction while the resilient frictional gripping of the outer shell 18 cooperates with the anchor rib 16 of the support to preclude movement of the feed-through terminal in the opposite direction unless subjected to considerable outside force. It is noted that the buffer 20 also supports the flange 15 to prevent the flange from breaking under additional pressure.

Thus, it is seen that a feed-through terminal is provided wherein the terminal element is rigidly supported by a material which is capable of withstanding the heat transmitted through the terminal element during subsequent soldering operations and further, the feed-through terminal is provided with a resilient outer shell to facilitate insertion of the feed-through terminal within a panel.

It is to be understood that the materials utilized in the support 14 and the shell 18 are not limited to those disclosed herein but could be any type of material which would satisfy the heat resistance and strengthening properties for the support and the resilient properties for the shell.

It is to be further understood that the above-described terminal is simply illustrative of the principles of the invention, other embodiments may be devised by those skilled in the art and still fall within the spirit and scope thereof.

What is claimed is:

1. A feed-through terminal insertable into and self-supportable in an aperture of a panel, which comprises:

a conductive element,
a rigid heat resistant thermosetting plastic support formed about an intermediate portion of the conductive element,
the support formed with a flange at one end thereof and a rib protruding outwardly along an intermediate portion thereof spaced from the flanged end a distance greater than the thickness of the panel, and
a cuplike shell of thermoplastic material having a groove formed within an intermediate portion of the inner wall thereof formed about the portion of the support extending from the flange with the rib of the support anchored within the groove of the shell so that the shell is precluded from moving in either direction relative to the support where, upon insertion of the feed-through terminal into the aperture of the panel, the flange of the support engages one surface of the panel to preclude continued movement of the terminal through the panel and the thermoplastic shell is compressed within the aperture and expands in a plane common with the support rib and adjacent the opposite surface of the panel to lock the terminal within the panel.

2. A feed-through terminal insertable into and self-supportable in an aperture of a panel, which comprises:
 a conductive element,
 a cylindrical support surrounding an intermediate portion of the conductive element having a diameter less than the diameter of the panel aperture,
 a circular flange formed on one end of the support having a diameter larger than the diameter of the aperture,
 an annular rib formed about an intermediate portion of the support axially displaced from the circular flanged end of the support a distance greater than the thickness of the panel, and
 a resilient cuplike shell formed about the portion of the support extending from the flange wherein the thickness of the shell provides an outer diameter for the feed-through terminal which is greater than the diameter of the panel aperture, the shell formed with an annular groove which mates with the rib of the support to anchor the shell with the support where, upon insertion of the feed-through terminal into the panel aperture, the resilient shell is deformed to fit into the smaller diameter panel aperture until the

support flange engages one surface of the panel, thereby positioning the rib in a plane spaced from the opposite surface of the panel so that the rib cooperates with the deformed resilient shell to lock the feed-through terminal within the panel.
